UNITED STATES PATENT OFFICE.

BARNETT B. WHALEY, OF BROOKLYN, E. D., NEW YORK.

IMPROVEMENT IN BUTTONS.

Specification forming part of Letters Patent No. 44,759, dated October 18, 1864.

To all whom it may concern:

Be it known that I, BARNETT B. WHALEY, of Brooklyn, E. D., in the county of Kings and State of New York, have invented a certain new and useful Improvement in Buttons as Attached to Garments; and I do hereby declare the following to be a full, clear, and exact description thereof, reference being had to the accompanying drawings, and to the letters of reference marked thereon, in which—

Figure 1 represents a piece of cloth with the piece of metal which holds the button attached thereto. Fig. 2 is a side view of button, showing the shank. Fig. 3 is an oblique view of button, showing the form of the shank more clearly. Fig. 4 is a vertical section showing the button attached to the cloth. Fig. 5 is an oblique view of the cloth with the button attached, the button being turned to one side to show the connection of the parts more distinctly.

My invention and improvement relate to attaching a metallic shank to the button in place of the ordinary eye, and a metallic disk to the garment, so that the button may be removed and another substituted in its place whenever required.

Among the advantages gained by my invention are the following: Military men, sailors, policemen, and others who wear distinctive buttons, if they wish to appear without their professional insignia, can readily remove their symbolic buttons and substitute a plain set. If a button becomes broken or disfigured, it can be removed and another substituted in its place. The button-fastening covering a larger portion of the cloth or garment than when the button is attached in the ordinary manner, the strain upon the cloth is distributed, and is consequently less liable to injure the garment and the button is less liable to break away from its fastenings and to come off.

a represents a metallic disk or plate, which is sewed or otherwise fastened to the garment *b*. There are six or more holes, *c*, drilled through it, by means of which it is sewed or fastened to the garment, thus distributing the strain more widely than when

the button is attached in the ordinary way. The central part of said disk or plate is stamped up, forming a conical elevation on the upper side of the disk or plate and a corresponding depression on the under side. Through the center of the disk or plate, and consequently through the center of the before-mentioned conical elevation, there is drilled a circular hole, *d*, with a slit or channel, *e*, running from said circular hole to the circumference of the disk or plate *a*, the width of said channel being less than the diameter of said central hole.

f is the button. *g* is the shank, which is attached to the lower part of the button in the same manner as the ordinary metallic eye. The lower part or end of the shank is formed into a head, the size of which shall correspond to the size of the depression stamped into the under part of the disk or plate *a*. The body of the shank immediately above said head is cylindrical, the diameter of said cylinder corresponding to the diameter of the before-mentioned circular hole *d*, drilled through the central part of the metallic disk or plate *a*. The upper part of the shank immediately below the button *f* is flattened by filing or stamping until the thickness of the flattened part shall correspond to the width of the channel *e* in the disk or plate *a*.

When it is desired to attach a button to a garment, the metallic disk or plate *a* is first sewed or fastened to the garment as represented in Figs. 1 and 5, or the disk may be sewed beneath the first thickness of cloth and a small opening or button-hole cut through the cloth for the passage of the shank. Then the shank of the button is pressed down against the cloth near the edge of the disk or plate *a* and close to the channel *e* until the flattened part of the shank enters the channel, along which it is slipped until it reaches the central part of the disk *a*, when the elasticity of the cloth forces it up, and the head of the shank fits into the depression in the central part of the disk or plate; or a small spring may be attached to the lower part of the disk to keep the head of the shank from working out of place.

The disk should always be attached to the garment in such a way that the channel *e* may open upward and the button *f* be slipped downward to its place.

Having thus fully described my invention, what I claim, and desire to secure by Letters Patent, is—

The combination and arrangement of the

shank *g* and the disk or plate *a* with the button *f*, and the cloth or garment *b*, substantially as and for the purpose set forth.

BARNETT B. WHALEY.
